ELECTRON DISCHARGE APPARATUS

Donald L. Snow, Hempstead, N. Y., assignor to
Sperry Gyroscope Company, Inc., a corpora-
tion of New York

Application November 29, 1943, Serial No. 512,222

9 Claims. (Cl. 250—27.5)

1

This invention relates to electron discharge apparatus and is particularly concerned with improvements in electron discharge apparatus of the hollow resonator type and methods of making the same.

Hollow resonator devices wherein an electron beam is passed in energy exchanging relation with the resonator field are known in various structural embodiments. The present invention represents mainly improvements in structure and assembly over such earlier devices, for providing an efficiently organized and operating combination of correlated parts.

It is, therefore, a major object of the invention to provide electron discharge apparatus of the hollow resonator type having novel construction and compact efficient arrangement of its component parts.

A further object of the invention is to provide electron discharge apparatus of the hollow resonator type wherein the parts producing and acting on the electron stream are aligned in a novel manner.

A further object of the invention is to provide a novel unitary sub-assembly for a hollow resonator electron discharge device, wherein a cathode, a hollow resonator and an electronic reflector are novelly mounted in predetermined relation; and to provide a novel method of assembling the same.

A further object of the invention is to provide a novel compact sub-assembly wherein the parts of a hollow resonator device effective upon the electron stream are permanently associated in a unitary mounting.

A further object of the invention is to provide hollow resonator apparatus arranged within an envelope and embodying novel thermally responsive frequency control structure associated with the resonator.

Further objects of the invention will presently appear as the description proceeds in connection with the appended claims and the annexed drawing, wherein:

Fig. 1 is an elevation, partly in section along line 1—1 of Fig. 3, of a hollow resonator type electron discharge device according to a preferred embodiment of the invention;

Fig. 2 is an elevation, partly in section, of the device of Fig. 1 but as viewed at an angle of about ninety degrees from the direction viewed in Fig. 1;

Fig. 3 is a section along line 3—3 of Fig. 1 providing a top view of the cathode, resonator, reflector unit in the assembly;

Fig. 4 is a fragmentary elevation of a sub-as-

2

sembly including a somewhat different resonator arrangement than that of Figs. 1—3; and

Fig. 5 is a substantially perspective view illustrating details of the cathode, resonator, reflector sub-assembly unit of Fig. 4, and manner of making the same.

Referring first to Figs. 1—3, the assembled high frequency device of the invention comprises a cylindrical metal envelope 11 and a base assembly 12. Base 12 has a bottom wall 13 made of some moldable insulation material such as a phenolic condensation product, and an upstanding metal collar 14 is secured to wall 13.

Envelope 11 and collar 14 are formed with integral radial flanges 15 and 16 which extend in coextensive contact with opposite sides of a relatively rigid metal plate 17. Preferably flanges 15 and 16 are permanently secured, as by welding or soldering, to plate 17. The seal between flange 15 and plate 17 is preferably vacuum tight so as to maintain a vacuum within envelope 11. The seal between flange 16 and plate 17 is preferably at least air tight to keep out dust and moisture.

25 A suitable thick stiffening plate 18 is secured as by welding to the upper surface of plate 17 so as to be disposed within envelope 11. If desired, plate 18 may be integral with plate 17. Any desired number of sealed conductor mounts, 30 for the device of Fig. 1, preferably five, are carried by plate 18. Some of these conductor mounts are indicated at 19 and 21—24.

Mount 19 comprises a short thin metal tube 25 extending through suitable apertures in plates 17 and 18 with its upper end flanged over the top surface of plate 18 as at 26. Tube 25 is suitably welded or similarly secured to plate 18 so as to provide a vacuum tight connection therewith. A short rigid conductor rod 27 imbedded in a glass or like insulating seal 28 axially within tube 25 has its upper end disposed within envelope 11 and its lower end suitably fastened to a hollow metal prong 29 rigidly supported on insulation wall 13 of the base.

45 Each of mounts 21—24 are of substantially identical structure with mount 19. As for those specifically illustrated, mount 21 supports a conductor rod 31 fastened to prong 32, mount 23 supports a conductor rod 33 fastened to prong 34, and mount 24 supports a conductor rod 35 fastened to prong 36. Thus all the conductors necessary for introducing required electrical energy for operation of the elements within envelope 11 enter the envelope through vacuum tight insulation seals.

55

Plates 17 and 18 are centrally apertured for mounting a thin malleable exhaust tube 37 which has its upper end sealed vacuum tight to plate 18 and is pinched off and closed at its lower end at 38 to complete sealing of envelope 11 after exhaust. Wall 13 is formed with a suitable molded depression 39 for accommodating exhaust tube 37.

All of the elements for producing and directly acting upon an electron beam within envelope 11 are preferably preassembled, prior to mounting in the device, in a permanent sub-assembly in which proper alignment is obtained and maintained as will later be explained.

The sub-assembly comprises a cathode or electron emitter unit 41 for producing an electron stream, an electron stream focusing or modulating electrode 42 surrounding the stream, a cylindrical hollow resonator unit 43 through which the electron stream is passed, and a reflector unit 44 for repelling and returning electrons of the stream into resonator unit 43.

Resonator 43 has its bottom wall fixedly mounted as by soldering within a suitable aperture in a rigid metal platform 45 extending parallel to plate 18. As shown in Fig. 1, resonator 43 is formed with a flexible annular top wall portion 46 surrounding a relatively rigid central region 47 which is centrally apertured at 48. Aperture 48 is aligned with a similar aperture 49 at the upper end of a reentrant conical hollow pole 51 integral with the resonator bottom wall. Wall portion 46 of the resonator is preferably an annularly crimped metal member which may be secured to or integral with the resonator side walls.

The circumference of platform 45 is formed with three equally spaced edge notches or recesses 52 permitting free passage of three parallel equally circumferentially spaced longitudinal support rods 53. Rods 53 are parallel to the longitudinal axis of the device and are made of insulating material. Preferably, rods 53 are bodies of glass or some other hardenable thermoplastic substance as will appear.

Glass rods 53 are rigidly and permanently mounted in parallel relation by means of three equally spaced stiff radial wires 54 which have their bent inner ends fixed by welding or soldering to platform 45 and have their outer ends imbedded within associated rods 53.

Cathode unit 41 is rigidly and permanently mounted in alignment with apertures 48, 49 by means of three equally spaced stiff radial wires 55 which have their inner ends fixed by welding or soldering to a flange 56 on the cathode unit and have their outer ends imbedded within associated glass rods 53.

Focusing electrode 42 is rigidly and permanently mounted in alignment with cathode 41 by means of three equally spaced stiff radial wires 57 which have their inner ends fixed by welding or soldering to electrode 42 and have their outer ends imbedded within associated glass rods 53.

Reflector unit 44 comprises a metal block having its lower reflecting surface 58 aligned with resonator aperture 48, and reflector unit 44 is rigidly and permanently mounted to so align surface 58 with the electron stream by means of three equally spaced stiff radial wires 59 which have their inner ends fixed by soldering or welding to reflector block 44 and have their outer ends imbedded within associated glass rods 53.

Fig. 2 illustrates the manner in which platform 45 is rigidly supported upon plate 18. A plurality of circumferentially spaced short posts 61 are

formed at their lower ends with threaded extensions 62 interfitting with suitable tapped holes in plate 18. The upper end of each post 61 is formed with a reduced threaded extension 63 which extends freely through an aperture 64 in platform 45 within a tapped central bore 65 in the lower end of an elongated post 66. Any suitable number of posts 61 and 66 may be thus provided although only two are illustrated. Posts 61 may first be mounted rigid with plate 18. Platform 45 is then seated upon the tops of posts 61, with extensions 63 projecting therethrough, and posts 66 are then mounted nut-like on extensions 63 to securely clamp platform 45 between the posts.

The upper ends of posts 66 are formed with reduced threaded extensions 67 which project freely upward through suitable apertures in a rigid bridge 68 generally parallel to platform 45. Bridge 68 is securely fastened to posts 66 as by nuts 69.

Plate 18, platform 45, bridge 68 and posts 61 and 66 thereby provide a strong rigid frame for supporting the elements of the device within envelope 11, and for withstanding strains incident to operation of the frequency control mechanism to be described.

Bridge 68 is formed with a large aperture 71 axially of the device. A plate 72 of electrical insulating material is securely mounted over aperture 71 by a sheet metal rim strip 73 which is welded or similarly fastened to bridge 68.

Plate 72 is also centrally apertured for mounting thereupon a shouldered metal terminal block 74 formed with a central bore into which extends the upper end of a relatively rigid electrically conductive strut or rod 75 of Duralumin or some other metal or alloy having a high coefficient of thermal expansion. Strut 75 is secured against axial movement within block 74, as by screw 76. Block 74 in turn is secured against displacement relative to plate 72, as by its illustrated interfitting engagement with the aperture in plate 72, and by peening or otherwise flanging its lower end at 77 over the adjacent lower surface of plate 72.

The lower end of strut 75 extends through the base of an inverted U-shaped bracket 78, and a suitable fastening element 79 anchors strut 75 to bracket 78. The opposite downwardly extending legs of bracket 78 are formed with shouldered terminals 81 interfitting with the upper ends of the corresponding upstanding legs of second U-shaped bracket 82. The base of bracket 82 is apertured and formed with an integral downwardly extending hollow boss 83 which is rigidly secured, as by soldering, to the resonator wall region 47 about exit aperture 48.

Strut 75 is coaxial with resonator 43 and located on the longitudinal centerline of the device. The purpose of the above described shape of brackets 78 and 82 is to obtain a solid connection between the lower end of strut 75 and the resonator wall region 47 without disturbing reflector unit 44 which is also located axially on that centerline. Reflector unit 44 extends within boss 83 for proper location relative to resonator aperture 48, but the parts are so dimensioned as to prevent contact between reflector 44 and bracket 82 during all conditions of operation.

Strut 75 is energized by current passing therethrough. Conductor rod 33 is welded or soldered to the lower end of a relatively stiff conductor 84 which has its radially bent upper end soldered or welded to block 74. A loose glass or like insu-

lating sleeve 85 supported by conductor 84 insulates it electrically against the electrically grounded frame parts such as platform 45. The lower end of strut 75 completes an electric circuit by grounding on the frame.

Cathode unit 41 is energized chiefly by a lead 86 from conductor rod 27, and a lead 87 supporting a glass insulating sleeve 88 is welded or soldered at opposite ends to conductor rod 31 and a conductor 89 rigid with reflector block 44. Other elements within envelope 11 are similarly suitably energized.

Ultra high frequency energy, in the neighborhood of 3×10^9 cycles per second and higher, is extracted from resonator 43 by means of a concentric transmission line section having a hollow outer conductor 91 and a coaxial inner conductor 92 supported and sealed therein by insulating beads of glass or polystyrene in a known manner. Outer conductor 91 passes through suitable apertures in plates 17, 18 and base wall 13. A short metal collar 93 upstanding from plate 18 surrounds outer conductor 91 and this joint is vacuum sealed to maintain the interior of envelope 11 vacuum tight.

As illustrated in Fig. 1, a conductive loop 94 interconnects the line conductors at their inner ends and projects through a suitable aperture in the bottom wall of resonator 43 for coupling with the ultra high frequency field within the resonator. The projecting lower end of the transmission line is externally available for connection to any utilization apparatus.

Figs. 4 and 5 illustrate an embodiment of the invention wherein a different type of resonator is mounted on platform 45. Here a relatively small diameter cylindrical resonator 95 has its bottom wall fixed as by soldering in a suitable central aperture in platform 45. The bottom wall of resonator 95 is formed with a hollow reentrant pole 96 having an aperture 97 aligned with a similar aperture 98 in the upper resonator wall 99. A bracket 82 is secured, as in Fig. 1, to the upper resonator wall about the exit aperture.

As illustrated in Fig. 4, the upper and side walls of resonator 95 are radially extended for an appreciable distance, and circumferentially joined. The purpose of this construction is to provide an upper resonator wall of sufficient area to safely provide adequate flexibility when the spacing between apertures 97 and 98 is varied during resonator tuning. Since this specific resonator structure is not part of the present invention, further description is unnecessary.

In the embodiment of Figs. 4 and 5, platform 45 is secured to glass rods 53 by three equally spaced stiff radial wires 101 which have their outer ends imbedded in rods 53 and are soldered or welded along the bottom surface of platform 45 as illustrated. The cathode, focusing electrode and reflector are secured in the sub-assembly exactly as in Figs. 1-3.

In operation, in both embodiments of the invention, a stream of electrons is projected by cathode 41 through resonator 43 (or 95) and is returned into the resonator by reflector 44 which is maintained at a suitable potential. The electron stream excites and maintains a high frequency field within resonator 43. Accepted theories of electron velocity modulation of the stream by interaction with the field to obtain this operation in such devices are explained in United States Letters Patent No. 2,250,511 to which reference is made for further detail.

Also in both embodiments, frequency control is accomplished by regulation of the temperature of

strut 75. Since strut 75 is anchored at its upper end to the rigid element supporting frame and connected at its lower end to the flexible resonator upper wall portion, elongation or contraction of strut 75 in response to temperature changes caused by variation of the electric current passed therealong results in displacement of aperture 48 respectively toward or away from aperture 49, thereby respectively proportionately decreasing or increasing the frequency of resonator 43. Control of the current passing along strut 75 is of course obtained by adjustment of a suitable external variable power source (not shown).

A very important feature of my invention is the sub-assembly of parts which produce or act directly on the electron stream. This is of particular importance where the resonator is small and has small electron permeable regions or apertures, as where ultra high frequencies are contemplated. Difficulty has been experienced during assembly of such devices in obtaining proper and reliable alignment of the cathode, resonator and reflector.

The present invention overcomes the above difficulties. As illustrated, the various elements of the sub-assembly comprising cathode unit 41, focusing electrode 42, platform 45 with the resonator (43 or 95) secured thereupon and reflector unit 44 are all mounted in desired alignment and related position by suitable jigs or fixtures designated at 102. Preferably bracket 82 is fixed to the resonator upper wall prior to this operation, which is of course performed only after the various sets of stiff radial wires above described have been soldered or welded to the elements.

Jigs or fixtures 102 are so designed that the free ends of the stiff radial wires are free, so that glass rods 53, heated until suitably plastic, may be forced onto the wires to imbed the ends of the latter therein. Rods 53 are allowed to remain impaled on the wire ends until cooled. When cooled, rods 53 become hard and rigid permanent insulation support and spacer members which maintain the elements in exactly the relation they were preset by jigs 102. No further alignment or adjustment operations are needed, and the whole assembly may be incorporated into the device by mounting platform 45 on posts 61 and making the necessary electrical connections.

If desired, apertures 48, 49 or 97, 98 may be provided with suitable wire mesh or like grids, although such are not essential where the apertures are small.

The above described construction provides a sturdy, compact hollow resonator device wherein the resonator and control elements are all mounted upon a strong rigid frame within the envelope, and which is assembled with a minimum of effort. The arrangements for precisely and permanently aligning the various elements producing or directly acting on the electron beam is especially important for hollow resonator devices embodying resonators of small volume and electron permeable areas of small size.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

What is claimed is:

1. High frequency electron discharge apparatus comprising a support, a platform carried by said

support, a hollow resonator mounted on said platform, a rigid body of electrical insulating material secured to said platform and electron emitter and deflecting electrode assemblies secured to said body and disposed on opposite sides of said resonator in alignment therewith.

2. The apparatus defined in claim 1, including an electron stream control electrode adjacent said emitter assembly also secured to said body.

3. High frequency apparatus comprising a platform, a hollow resonator mounted on said platform and having electron permeable regions, a plurality of laterally extending supports secured to said platform, a cathode mounted at one side of said resonator for supplying a stream of electrons for passage through said regions, a plurality of laterally extending supports secured to said cathode, an electrode mounted at the other side of said resonator for reflecting said electron stream into said resonator, a plurality of laterally extending supports secured to said reflector electrode, and a plurality of rigid electrical insulating bodies peripherally spaced about said platform and secured to said lateral supports and fixedly maintaining said cathode, resonator and reflector electrode in desired alignment.

4. The apparatus defined in claim 3, including a focusing electrode adjacent said cathode for controlling said electron stream, and a plurality of laterally extending supports secured to said focusing electrode and to said rigid bodies.

5. High frequency apparatus comprising an electron emitter assembly, a hollow resonator assembly and an electron repelling electrode assembly all mounted in predetermined alignment, a plurality of circumferentially spaced bodies of rigid electrical insulating material, and lateral supports projecting from said assemblies and secured to said bodies and individually attaching said assemblies to said bodies.

6. High frequency electron discharge apparatus comprising a base, a frame rigid with said base, a

support on said frame, and means carried by said support substantially permanently mounting a cathode assembly, a hollow resonator assembly and a reflector assembly in alignment.

7. High frequency apparatus comprising a support, a hollow resonator having a portion movable for varying the frequency of said resonator mounted on said support, a cathode structure mounted on said support in alignment with said resonator, a frame structure secured to said support, and a thermally responsive frequency control member having a rigid electrically insulated connection to said frame at one end and a rigid connection to said movable portion at its other end.

8. High frequency apparatus comprising a base, an envelope rigid with said base, a plurality of posts upstanding from said base within said envelope, a support mounted on said posts, a hollow resonator mounted on said support, a cathode structure mounted on said support in alignment with said resonator, a bridge extending across the ends of said posts remote from said base, an electrical insulating member fixed to said bridge, and an electrically conductive frequency control member secured at opposite ends to said insulating member and said resonator.

9. High frequency apparatus comprising a base, an envelope enclosing a space adjacent said base, a plurality of post members projecting from said base into said space, a support mounted on said post members, a hollow resonator having electron permeable regions mounted on said support, means fixed to said support for producing an electron stream for passage through said regions, a bridge extending across the ends of said post members remote from said base, an electrical insulating member fixed to said bridge, and an electrically conductive frequency control rod secured at opposite ends to said insulating member and said resonator.

DONALD L. SNOW.
